United States Patent Office

Des. 192,835
Patented May 15, 1962

192,835

TAPE DISPENSER OR SIMILAR ARTICLE

Bernard M. Wax, 45 Pine Grove Ave., Sharon, Mass.

Filed May 9, 1960, Ser. No. 60,489

Term of patent 14 years

(Cl. D74—1)

FIG. 1

FIG. 2

FIG. 3

I claim:

The ornamental design for a tape dispenser, as shown.
